CORPORATION OF DELAWARE.

DUPLICATING DEVICE FOR ADDING MACHINES.

Application filed September 11, 1920. Serial No. 409,689.

To all whom it may concern:

Be it known that we, WILLIAM H. FENN and OSCAR E. GROSELL, residents of Wilmington, county of New Castle, State of Delaware, both citizens of the United States of America, have invented certain new and useful Improvements in Duplicating Devices for Adding Machines, of which the following is a true and exact description, reference being had to the accompanying drawings, which form a part thereof.

Our invention relates to adding or like computing machines and has for its object to provide in connection with the printing mechanism of such machines simple and efficient mechanism whereby the printing is effected on two strips of paper, one of which is rolled up on the machine to form a permanent record and the other of which is so fed from the printing mechanism that it can be readily torn off in sections.

The nature of our improvements and their mode of operation will be best understood as described in connection with the drawings in which they are illustrated and in which—

Figure 1 is a side elevation showing part of the mechanism of an adding machine of familiar type and our improved duplicating mechanism in operative relation thereto.

Figure 2 is an elevation taken in front of the printing platen and showing the ink ribbon rolls, mechanism for spacing the inking ribbons, the cut off bar or knife and the front edge of the table over which the paper strip on which the permanent record is formed is fed.

Figure 3 is a similar elevation showing the spacing plate in operative position.

Figure 4 is a cross sectional view taken on the line 4—4 of Fig. 3, and

Figure 5 is a plan view of the ribbon rolls and the spacing and tension devices by which the two inking ribbons are held properly taut.

A indicates the framework of the adding machine, B one of the keys, C one of the slide plates supporting a type holding head C⁴ and formed as shown with slots C' C² C⁷ and through which extend guide rods C³ C⁸ for properly aligning the slide. C⁴ is the end of a lever by means of which the head C is elevated, C⁵ the end of a second lever having a crossbar C⁶ for moving down the several levers C⁴ and their attached slides. C⁸ in-

dicates a shoulder on the slide, D D etc., 55 indicate printing type held in the type heads C'. E is a shaft extending across the machine and supporting the pivoted levers E' E², the arm E² of the lever being connected through a link E³ with a lever E⁴ E⁵ pivoted on the shaft E'. The arm E⁵ of the lever has pivoted upon it the latch lever F F', which is normally slotted and held in engaging position by the action of the spring F³ attached to the end of the lever arm 60 E⁵ and to a lug F² of the lever F. G indicates one of the strikers pivoted on the shaft E⁶ and having a striking head as indicated at G' which registers with the different type bars as the printing head moves up and 70 down; the striking lever G has an arm G² normally resting against the stop G³ through the action of a spring G⁴ and having a hook engaging lug G⁵ which is normally engaged by the hook lever F. 75

The above described features of the adding machine are all of well known construction and form no part of our invention.

H indicates the printing platen which is a roll secured to the shaft H' and intermittently actuated through the ratchet wheel H². I is a lever having a cam head I' resting in contact with the roller E' at the end of the lever E⁴. This lever is pivoted on a shaft I³ and has a slotted arm 80 I² through which it is adjustably connected with a bent lever I⁴ pivoted on the shaft H' and having pivoted to it through the stud I⁵ a pawl J having a finger J' extending from it and an attached spring J² which tends to draw it into contact with the ratchet H². Pivots connected to the lever I⁴ is the connecting rod K which is also pivotally connected to the rock lever K² pivoted on the shaft K⁵ and carrying a spring actuated 90 pawl K³ which engages a ratchet wheel K⁶ and through it actuates the take up roller K⁶. L L' is a lever pivoted on the shaft L³ and carrying a ratchet detent L² on its arm L and having attached to its arm L' a spring 100 L⁴. M, M', is a pivoted lever having on its arm M a ratchet detent M² and attached to its arm M' a spring for holding the detent against the ratchet K⁴. N is a bracket reaching out from the back of the machine and supporting the rod N' on which is journaled the paper roll N³, N² being a latch lever for holding the roll in position and N⁴ indicating 105

the paper strip from the roller N^3 which passes over the rod L^3 over the front of the platen H and thence up over a flat table indicated at P' and thence to the take-up roll K^6 . O, O' , is a bent lever pivoted on the rod L^3 and carrying a roller O^2 on its arm O' which is pressed against the platen by the action of a spring O^4 . O^3 is a finger contact on the arm of the lever O by which it can be turned when it is desired to separate the roller O^2 from the platen. P is a knife bar located above the platen and in front of and somewhat below the edge of the table P' . Q is a bracket extending out from the back of the machine and supporting the rod Q' which in turn supports the paper roll Q^3 from which the paper strip Q^4 extends up over the shaft L^3 over the front of the platen and back of the knife P , as shown. R is a pivot stud on which is pivotally supported the spacing plate R' in such position that the plate can be turned off to one side of the platen as shown in Fig. 2 or turned up to lie in front of the platen as shown in Fig. 3. The edge R^2 of the plate R' is curved so that when the plate is turned up to operative position the two ribbons are spaced apart to give ready access to the paper strip Q^4 . The plate R' is also preferably provided with an arm or finger R^3 having preferably a shoulder R^4 which in turned up position rests against the knife P , the finger extending up in front of and above the table P' . S, S' , are brackets for supporting the inking ribbon rolls. These brackets support the roller pivots S^2 and S^3 on which are journaled the ink ribbon rolls S^4, S^5 , to which are attached the ratchet wheels S^6, S^7 . S^8 and S^9 indicate 40 detent ratchets operating in connection with the ratchets S^6 and S^7 . T, T' , indicate arms of the brackets which support spacing rollers indicated at T^2, T^2 . T^3, T^4 , are spring supporting guide rods indicated at T^4, T^4 . U, U' , are levers pivoted on the rods S^2 and S^3 and carrying arms U' to which are attached the levers actuating the ratchets indicated at U^2, U^2 . The levers U^2 are operatively connected by a bent bar U^3 and are connected through a pivoted lever U^4, U^5 , and an actuating lever U^6 connected with moving parts of the machine in any convenient way.

In operation the slide C carrying the type ends C' are moved up and down by the lever C^4 actuated by the keys B each key calling for the registry of one of the vertical row of type D with a head G' of the hammer lever G . The hammer lever is actuated directly through the lever E' which being moved toward the right transmits motion through the lever E^3 to the lever E^4, E^5 pulling down on the ratchet lever F which through the detent G^6 pulls down the lever 65 arm G against the tension of the spring G^4 .

and locates and rocks the hammer lever G backward until the end of the lever F' comes in contact with the shoulder C^8 of the slide C when the latch releases the detent G^5 and the hammer springs forward 70 against the type and this is the familiar operation of the well known adding machine.

As the lever arm E^4 moves toward the right its end E^7 contacts with the cam end I' 75 of the lever I, I^2 , and rocks the bent lever I^4 downward and the pawl J being in engagement with the ratchet H^2 the platen H is given a rotative movement. The same movement of the lever I^4 transmits movement through the link K to the lever K^2 on which is pivoted the pawl K^3 which through the ratchet K^4 transmits motion to the take-up rollers K^6 . The link K has projecting from it a latch or finger K' which lies under 80 a finger J' attached to the pawl J and coming in contact with it lifts the pawl out of engagement with the ratchet wheel H^2 before the lever I^4 has completed its full movement. As a consequence the take-up roller 85 K^6 is fed through a considerably greater arc than the platen roller H with the result that the paper extending between the platen roll of the take-up roll and the table P' , is kept taut upon the table and is wound up on the 90 take-up roll K^6 . The paper from the roll Q^3 also passes over the rod L^3 and over the platen roller in front of the paper strip N^4 and comes up under the knife bar P against which it is torn off in sections to 95 suit the operator.

The inking ribbons t' are wound on the spools S^4, S^5 , from each spool they pass above and below a spacing roller T^2 and then over the torsion guide rods T^4, T^4 , which 105 hold the ribbons in proper alignment in front of the platen. The spacing roller and guide rods are so located with reference to the spools as to prevent slack in either of the two ribbons in the space between the rods T^4 , 110

Motion is given to the inking ribbons through a lever U^6 connected with the operative part of the adding machine and giving a reciprocating motion through the crank lever U^4, U^5 , to the bent connecting 115 bar U^3 which gives an oscillating movement to the lever arms U, U' , and through arms U' and pawls U^2 to the ratchet wheels S^6 attached to the spools. The ratchet wheels and spools are held stationary during the reverse 120 movement of the actuating pawl by the detents S^8, S^9 .

It is a very simple matter to feed the paper strip N^4 up between the platen and the inking ribbon T' . It is more difficult, however, to fit in a new strip Q^4 between the two inking ribbons and to facilitate this we provide the pivoted spacing and paper guiding plate R' with its curved edge R^2 which normally lies in the position indicated in 130

Fig. 2 in which its curved edge performs a useful function in slightly spacing the two inking ribbons apart. When it is desired to insert a new strip Q^1 the plate R' is turned 5 to the position shown in Figs. 3 and 4 in which position its curved end thrusts the ribbon t' upward and provides a clear path between the ribbon t' and the inner face of the plate R' for the passage of the paper 10 strip, as best shown in Fig. 4. In this position, also, the finger R^3 extends up in front of the table P' and affords a convenient resting place for the roll N^3 which it is advisable to detach when inserting a new slip N^4 .

15 It will be understood that in inserting the paper strips the lever arm O is moved toward the left depressing the contact roller O^2 .

While we have shown and described our invention as applied to a machine having 20 only two inking ribbons and two paper rolls, it will be obvious that it can be applied to machines having a greater number of inking ribbons and paper rolls and we wish it to be clearly understood that our claims are not 25 to be understood as limiting our invention to machines having not more than two inking ribbons.

Having now described our invention, what 30 we claim as new and desire to secure by Letters Patent is,

1. In combination with the printing mechanism of an adding machine means for duplicating the printing comprising two inking ribbons and means for feeding them across 35 the platen, means for feeding paper strips over the platen, including a take up roll on which the strip lying next to the platen is rolled up, a table lying above the platen and between it and said roll over which the said 40 strip passes and a cutter bar lying above the platen and in front of the table for severing sections of the outer paper strip.

2. In combination with the printing mechanism of an adding machine means for duplicating the printing comprising two inking ribbons and means for feeding them across 45 the platen, means for feeding paper strips over the platen, including a take up roll on which the strip lying next to the platen is rolled up and means for rotating the platen 50

through a small arc and the take up roll through a larger arc acting in synchronism with the printing mechanism.

3. In combination with the printing mechanism of an adding machine means for duplicating the printing comprising two inking ribbons and means for feeding them across the platen, means for feeding paper strips over the platen, a spacing plate pivoted to the machine frame and extending between 55 the ribbons and movable from a position in which it lies in front of the platen to one at one side thereof, said plate having a curved edge for spacing the ribbons.

4. In combination with the printing mechanism of an adding machine means for duplicating the printing comprising two inking ribbons and means for feeding them across the platen, means for feeding paper strips over the platen, including a take up roll on 60 which the strip lying next to the platen is rolled up, a table lying above the platen and between it and said roll over which the said strip passes, a cutter bar lying above the platen and in front of the table for severing 65 sections of the outer paper strip, a spacing plate pivoted to the machine frame and extending between the ribbons and movable from a position in which it lies in front of the platen to one at one side thereof, said 70 plate having a curved edge for spacing the ribbons, and a finger which when turned up extends in front of and above the table.

5. In combination with the printing mechanism of an adding machine means for duplicating the printing comprising two ribbon rolls having two ribbons wound upon them and extending in front of the platen roll, means for maintaining the ribbons in proper 85 tension comprising spacing rolls spaced with 90 respect to the ribbon rolls so as to maintain both ribbons in tension, means for feeding paper strips over the platen and a spacing plate adjustable to and from operative position for spacing the ribbons in front of the 95 platen when the outer paper strip is to be inserted between the ribbons.

WILLIAM H. FENN.
OSCAR E. GROSHELL.
